CLAIM

The ornamental design for a mobile phone, as shown and described.

DESCRIPTION

1. Mobile phone
2. Mobile phone
3. Mobile phone
4. Mobile phone
5. Mobile phone
6. Mobile phone

2.1 is a front view of a first embodiment of a mobile phone, showing our new design;

2.2 is a back view thereof;

2.3 is a left side view thereof;

2.4 is a right side view thereof;

2.5 is a top plan view thereof;

2.6 is a bottom plan view thereof;

2.7 is a front perspective view thereof;

2.8 is a back perspective view thereof;

5.1 is a front view of a second embodiment of a mobile phone;

5.2 is a back view thereof;

5.3 is a left side view thereof;

5.4 is a right side view thereof;

5.5 is a top plan view thereof;

5.6 is a bottom plan view thereof;

(Continued)

5.7 is a front perspective view thereof; and
 5.8 is a back perspective view thereof.

The broken lines show portions of the mobile phone that form no part of the claimed design in the embodiments in which they are shown.

1 Claim, 12 Drawing Sheets
